UNITED STATES PATENT OFFICE.

JOHN WILSON BROWN, JR., OF PHILADELPHIA, PENNSYLVANIA.

DESIGN FOR A GRINDING-DISK FOR MILLS.

SPECIFICATION forming part of Design No. 29,029, dated July 12, 1898.

Application filed April 28, 1898. Serial No. 679,144. Term of patent 14 years.

To all whom it may concern:

Be it known that I, JOHN WILSON BROWN, Jr., a citizen of the United States, residing in Philadelphia, Pennsylvania, have invented a 5 certain new and useful Design for a Grinding-Disk for Mills, of which the following is a specification.

My design for the grinding-disk of a mill is clearly illustrated in the accompanying 10 drawings, in which—

Figure 1 is a face view of the disk; and Fig. 2 is a sectional view on the line xx , Fig. 1. The essential feature of the design is the 15 dished base having a curved surface, from which project a series of ribs, some of which are longer than the others, the upper surface of the ribs being at right angles to a line drawn through the center of the disk.

A is the base, having the surface a curved from a point a' to the periphery a^2 of the disks. 20 $b b' b^2$ are a series of ribs extending around the surface of the disk. The ribs b are short. The ribs b' extend beyond the ribs b , while the ribs b^2 extend beyond the ribs b' and are arranged in the manner shown in the drawings. 25

I claim—

The design for the grinding-disk of a grinding-mill as herein described and as illustrated in the accompanying drawings.

In testimony whereof I have signed my 30 name to this specification in the presence of two subscribing witnesses.

JOHN WILSON BROWN, JR.
